UNITED STATES PATENT OFFICE

WILLIAM A. VOLLMER, OF KENOSHA, WISCONSIN, ASSIGNOR TO SIMMONS COMPANY,
OF NEW YORK, N. Y., A CORPORATION OF DELAWARE

CUSHIONED TIP

Application filed November 21, 1927. Serial No. 234,603.

This invention relates to tips for chair legs or the like, and more particularly to tips having a cushion for engaging the floor on which the chair or other article of furniture 5 is supported.

The objects of the invention are to provide a simple cushioned tip construction which can be cheaply and economically manufactured; to provide a cushioned tip having 10 means whereby the same may be mounted in the lower end of a chair leg or the like and particularly in the lower end of a tubular metal leg; to provide a tip which will not be likely to scratch or otherwise mar the floor 15 which it engages, even after the cushion element is worn away to such an extent that it no longer supports the load; to provide a tip structure which can be easily and quickly removed and replaced with a new tip when 20 the first one becomes worn; and in general, to provide an improved tip of the class described.

Other objects and advantages of the invention will be understood by reference to 25 the following specification and accompanying drawing in which I have described and illustrated a selected embodiment of the invention.

In the drawing:
30 Fig. 1 is a side elevation of a tip embodying my invention.

Fig. 2 is a section through the axis of the tip, and showing the same as it appears when mounted in the lower end of a tubular metal chair leg or the like, and 35

Figs. 3, 4, 5 and 6 are sections illustrating successive steps in construction of my improved tip.

Referring now to the drawing, my improved tip includes a mounting member 10 which consists of a base plate portion 11 having a recess or socket 12 formed therein and upwardly extending arms 13 and 14 which frictionally engage the inside of the 45 leg to hold the mount therein.

The marginal or edge portion of the base plate is turned upwardly, as shown at 16, and inwardly to form an annular shoulder 17 for receiving the lower end 18 of the chair 50 leg, thereby to limit inward movement of

the mounting member in the leg. The arms 13 and 14 are preferably integral with the base plate so as to constitute a one piece mounting member, and the same extend upwardly from the inner edge of the shoulder 55 17. Portions of the arms 13 and 14 are preferably widened, as shown at 19 and 20, and shaped in cross section so as to conform to the shape of the inside of the leg which they are intended to engage, thereby to increase the area of frictional engagement so as to securely hold the mount in place on the leg. The upper ends 21 and 22 of the arms 13 and 14 respectively, are preferably somewhat narrowed and extend inwardly towards 60 each other into abutting engagement as shown at 23, in Fig. 2, the extremities of the arms being preferably turned upward to form relatively wide engaging surfaces. 65

As best shown in Fig. 1, the upwardly-extending arms 19 and 20 are preferably swung apart somewhat, so that their upper ends do not abut when the tip is not mounted in a leg. It will be understood that when the mount is inserted into the inside of the 70 leg, the arms 19 and 20 are compressed towards each other so as to establish the abutting engagement at their upper ends, as shown in Fig. 2. Such engagement then serves to prevent too free flexing or compression of the arms towards each other and causes further compression to be effected by 75 springing or flexing of the narrower upper end portions 21 and 22 of the arms. It will thus be seen that the mount will be 80 firmly held by frictional engagement in the recess of the leg. 85

The recess 12 provided in the base plate 11 is for the purpose of receiving a cushion member which preferably includes a cushion 90 plug or element 24 and a cup-shaped member 25. The cup-shaped member is formed with an inwardly projecting annular flange portion 26 which is continued outwardly and rearwardly, as shown at 27, so as to 95 form a smooth, preferably convex, outwardly facing bottom edge or surface 28, and also so as to engage the base plate 11 as shown at 29. The bottom surface 28 is 100 preferably convex, but any smooth surface,

free from sharp corners, will be quite servicable. The cup is secured in the recess preferably by being spot-welded to the bottom wall of the recess as shown at 30, and the cushion member 24, preferably of compressible material, such as felt, is locked in place in the cup member in any suitable manner, for instance, by having a portion intermediate its inner and outer ends compressed by the inwardly projecting annular flange 26. It will thus be seen that the cup member is securely fastened in place in the recess of the mounting member 10, and that the cushion member is releasably locked in the cup member.

It will be apparent that when the cushion member wears down completely, the entire tip structure may be replaced by withdrawing the mount from the chair leg and replacing it with a new one, or the cushion element alone may be removed from the cup part and a new cushion element inserted. It will further be noted that when the cushion member 24 wears down to the point where it no longer sustains any of the load of the article which it is intended to support, the outwardly facing cornerless (free from sharp corners) edge 28 of the cup member will take up the load, and being smooth, as above described, will not scratch or mar the floor or other surface on which it rests, even though the article which it supports is slid across such surface.

In Figs. 3, 4, 5 and 6, certain of the steps in the manufacture of my improved tip are shown. Fig. 3 is a section showing the lower end portion of the mounting member as it appears before the recess 12 is formed therein. The mounting member is initially formed with a convex bottom surface 31, which in itself is adapted to glide smoothly over a floor without scratching the same. Hence, my improved tip structure includes an element which of itself forms a complete and operative tip.

For changing this initial tip structure from the convex surfaced type to a cushioned tip, I force the convex portion 31 inwardly of the tip to form the recess 12 as shown in Fig. 4. A cup member having a bottom wall 32, side wall 33 and outwardly extending annular rim flange 34, is then seated in the recess 12 and secured therein preferably by spot-welding the bottom wall 32 of the cup to the bottom wall of the recess 12. The portion of the wall 33 of the cup adjacent the flange 34 is then swaged inwardly to form the inwardly projecting annular shoulder 26 as shown in Fig. 6. During this operation, the cushion member may or may not be seated in the cup. If the cushion member is so seated, it will be obvious that the same will be interlocked with the cup when the annular shoulder 26 is formed therein, a portion of the cushion

being compressed as shown at 35 during the formation of the said annular shoulder. After the shoulder is thus formed, the outwardly extending annular flange 34 is turned rearwardly of the cup into engagement with the base plate 11 of the mounting member so as to form the outwardly facing rounded bottom face 28, as shown in Fig. 2.

If the cushion member 24 is not seated in the cup when the shoulder 26 is formed, the cushion may be inserted after the rounded face 28 is formed on the cup, the shoulder 26 being effective to sufficiently compress the cushion member to lock it in place.

The tip thus formed presents a neat appearance, is strong and serviceable, and may be readily replaced when necessary.

The above described details of construction are merely illustrative of a single embodiment of the invention, for which reason the scope of the same should be determined by reference to the following claims, which should be construed as broadly as possible consistent with the state of the art.

I claim as my invention:

1. In a tip of the class described, the combination of a cup-shaped member, a cushion seated in said member and projecting therefrom, and means for mounting said cup member and cushion on a leg or the like having a recess in its lower end, said means comprising a one-piece member having an end wall provided with a recess for receiving said cup member, the outer edge of said end wall being turned upwardly and inwardly to form a shoulder for receiving the lower end of said leg, and a plurality of arms, integral with said end wall and extending upwardly from the inner edge of said shoulder for entering said recess and frictionally engaging a portion of the side wall thereof.

2. In a tip of the class described, the combination of a cup-shaped member including bottom and side walls, the rim portion of the side wall being turned inwardly, then outwardly, and then rearwardly, so as to form an inwardly projecting shoulder and a smooth, cornerless, outwardly facing edge on the cup, a cushion seated in said cup and having a portion compressed by said inwardly projecting shoulder for locking the cushion in the cup, and means for mounting the cup and cushion on a leg or the like having a recess in its end, comprising a one-piece member including an end wall provided with a recess for receiving said cup, the outer edge of said end wall being turned upwardly and inwardly to form a shoulder for receiving the lower end of said leg, and a plurality of arms integral with said end wall and extending upwardly from the inner edge of said shoulder, for entering said recess and frictionally engaging the side wall thereof.

3. A tip of the class described, including a compressible cushion member, means for mounting the cushion member on the end of a leg or the like and including a cup-shaped member adapted to receive said cushion, said cup member comprising bottom and side walls, the rim portion of the side wall being turned inwardly, then outwardly, and then rearwardly, so as to form an inwardly projecting shoulder adapted to compress a portion of the cushion intermediate its ends for locking the cushion in the cup and so as to form an outwardly facing cornerless edge portion on the cup, which edge portion is adapted to slide over a floor surface or the like, without scratching or injuring the same when the cushion member is worn away. 5
4. A tip of the class described, including a compressible cushion member, means for mounting the cushion member on the end of a leg or the like and including a cup-shaped member adapted to receive said cushion, said cup member comprising bottom and side walls, the rim portion of the side wall being bent so as to form a flange extending inwardly from and laterally of the side wall of the cup member, for engaging and locking the cushion in the cup, and said rim 20 portion being also bent so as to form an outwardly facing cornerless edge portion on the cup, which edge portion is adapted to slide over a floor surface or the like, without scratching or injuring the same when the cushion member is worn away. 25
5. In a tip of the class described, the combination of a cup-shaped member having bottom and side walls, the rim portion of the side wall being turned inwardly, then outwardly, and then rearwardly, so as to form an inwardly projecting shoulder and a smooth, rounded, outwardly facing edge on the cup, a cushion seated in said cup and having a portion compressed by said inwardly projecting shoulder and thereby interlocked with the cup, and means for mounting the cup and cushion on a leg or the like having a recess in its end, said means comprising a one-piece member including an 40 end wall, the outer edge of which is turned upwardly and inwardly to form a shoulder for receiving the lower end of the leg, and a plurality of arms integral with said end wall and extending upwardly from the inner edge of said shoulder for entering the recess in the leg and frictionally engaging the side wall thereof. 45
6. In a tip of the class described, the combination of a cup-shaped member including a bottom wall and a side wall, the rim portion of the side wall being turned inwardly, then outwardly, and then rearwardly, to form an inwardly projecting shoulder and a smooth, outwardly facing, convex edge on the cup, a cushion seated in said cup and hav- 50
- ing a recess intermediate its ends for receiving said shoulder, whereby the cup and cushion are interlocked, means for mounting the cup and cushion on a hollow leg or the like, comprising a one-piece member including an end wall provided with a recess for receiving said cup, the outer edge of said end wall being turned upwardly and inwardly to form a shoulder for receiving the lower end of said leg, and a plurality of arms integral with said end wall and extending upwardly at opposite sides of the end wall from the inner edge of said shoulder, said arms being adapted to be compressed toward each other so as to be capable of snugly fitting the inside of the leg and frictionally engaging the same, the upper ends of said arms being bent inwardly towards each other and in abutting engagement when the arms frictionally engage the inside of the leg, thereby to insure tight frictional engagement between said arms and the inside of the leg. 55
7. In combination, a cushion tip member, and means for mounting said tip member on a leg or the like provided with a recess in its end, said means comprising a one-piece mounting member including an end wall provided with a recess for receiving said cushion member, the outer edge portion of said end wall being turned outwardly, upwardly, and inwardly so as to form a shoulder for receiving the end of the leg, a plurality of arms integral with said end wall and extending upwardly from the inner edge of said shoulder, for entering the recess in the leg and frictionally engaging the side wall thereof. 60
8. In combination, a cushion tip member, and means for mounting said tip member on a leg or the like provided with a recess in its end, said means comprising a one-piece mounting member including an end wall provided with a recess for receiving said cushion member, the outer edge portion of said end wall being turned outwardly, upwardly, and inwardly so as to form a shoulder for receiving the end of the leg, a plurality of arms integral with said end wall and extending upwardly from the inner edge of said shoulder, for entering the recess in the leg and frictionally engaging the side wall thereof, and means interlocked with the periphery of the cushion member for locking the cushion in said recess. 65
